(57) **CLAIM**

The ornamental design for spectacles as shown and described.

DESCRIPTION

1. Spectacles

1.1 : Perspective

1.2 : Front

1.3 : Back

1.4 : Right

1.5 : Left

1.6 : Top

1.7 : Bottom

With reference to the drawings, the present design relates to spectacles comprising a front frame carrying two lenses, and two temples articulated to opposite sides of said front frame; according to the present design, at the junction of each temple with the front frame, each temple provides a decoration shaped essentially like two opposing C letters, with a rectangle with rounded vertices interposed and interlaced with the C letters; in the representations of the design, the light colored parts indicate disclaimed features for which protection is not being sought.
